UNITED STATES PATENT OFFICE.

MAURICE DE GEYNST, OF FOREST-BRUSSELS, AND IVAN LEPAGE, OF DIEGHM,
BELGIUM.

BLANK CARTRIDGE.

Application filed November 30, 1927, Serial No. 236,724, and in Belgium November 30, 1926.

This invention has reference to improvements in or relating to blank cartridges for use with firearms and is more particularly concerned with blank cartridges for use with small arms of the kind in which the ejection of the empty case and the loading of a new cartridge is effected by the backward and forward motion of the bolt.

In order that each firing of a blank cartridge may be complete it is necessary that the re-coil produced by the discharge of the dummy bullet should be sufficient to ensure the automatic ejection of the empty case. Heretofore it has been proposed to solve the problem by increasing the weight of the cartridge by partially filling it with a heavy granular substance.

The present invention solves the same problem by employing as a charge two explosives of different degrees of inflammability the slower burning powder preferably being disposed in close proximity to the dummy bullet or the like which contains it.

The difference in the degree of activity between the two powders produces an appreciable recoil without affecting in any way the discharge of the dummy bullet or the pulverization thereof after leaving the barrel.

The drawing appended hereto shews in longitudinal vertical section and by way of example one means of carrying the invention into effect.

The blank cartridge shewn in the drawing comprises a hollow dummy bullet 1 which is made in the usual manner and of any suitable material, said dummy bullet being filled with a relatively slow burning powder 2. This dummy bullet is inserted in a case 5 which is filled with a powder 4 said powder 4 being of a relatively quicker burning quality than the powder 2 filling the dummy bullet. The cartridge is provided with the usual percussion cap or detonator which is denoted by the reference numeral 6.

The charges 2 and 4 are preferably separated by a wad of paper wool 3 which, however, can be dispensed with if desired.

The charge of powder 4 for filling the case may itself, if desired, be made of two powders

of varying degrees of inflammability in which case the dummy bullet can be filled with the same charge instead of a special powder.

It should be remarked that the various forms of the invention all tend towards the same aim, namely, to obtain a delay in the explosion of a part of the charge of the cartridge.

It will be appreciated that the dummy bullet will be made in known manner from material which is reduced to a dust on leaving the barrel, said bullet, nevertheless, being of sufficient strength to maintain a definite shape and to ensure a completion of the firing operation without involving the deformation thereof.

Blank cartridges constructed in accordance with the present invention offer the advantage that they allow of the simulation of war conditions of firing without the resultant danger.

What we claim is:—

1. A blank cartridge for firearms comprising a cartridge case, a dummy bullet secured in the front of said case, a charge disposed within said case of two or more explosives of different degrees of inflammability whereby an interval is obtained between the time of explosion of the portions of the charge which results in a re-coil which effects the automatic ejection of the empty case.

2. A blank cartridge for firearms comprising a cartridge case, a dummy bullet secured within said case, a relatively slow burning charge contained within said bullet, a more active charge contained in said case and a wad interposed between the two charges.

3. A blank cartridge for firearms comprising a case, a hollow dummy bullet inserted in the end of said case, a charge of relatively quick burning powder contained within said case, a charge of relatively slower burning powder contained within said bullet, a wad separating the two charges, and a percussion cap secured within the end of said case.

In testimony whereof, we have signed our names to this specification.

MAURICE DE GEYNST:
IVAN LEPAGE.
